ATTORNEY

UNITED STATES PATENT OFFICE.

ROBERT C. DEALE, OF PLAINFIELD, NEW JERSEY, ASSIGNOR TO NILES-BEMENT-POND COMPANY, OF NEW YORK, N. Y., A CORPORATION OF NEW JERSEY.

SWITCH STRUCTURE.

Application filed July 16, 1924. Serial No. 726,347.

My invention relates to switch structures and particularly to switches for controlling the operation of planers and similar machine tools.

5 One object of my invention is to provide a new and an improved pilot switch that shall be simple in construction and operation and that shall be adapted for governing the operation of planers and similar machine tools.

10 Another object of my invention is to provide a switch that shall comprise a number of sets of stationary contact members disposed in circular arrangement and a number of movable contact plates each of which is located between two sets of contact members so that rotation of the contact plates in either direction bridges a set of the contact members.

15 20 In the accompanying drawing:

Figure 1 is a plan view, with a portion of the cover removed, of a switch constructed in accordance with my invention.

Fig. 2 is a sectional view along the line 25 2—2 of Fig. 1.

Referring to the drawing, a switch is illustrated comprising a base 1 having a cover 2 secured thereto by means of bolts 3. The base 1 is secured to a wall of the machine 30 tool (not shown) by means of the projecting lugs or legs 4. By so mounting the switch a distance from the supporting wall, it should be noted that the bolts 3 for securing the cover 2 to the base are easily withdrawn 35 for inspection or replacement of any part of the switch. Moreover all moving parts of the switch are well protected.

A small shaft 5, which projects through the base 1, carries a plate of insulating material 6 near one end thereof. An operating lever 7 is keyed to the opposite end of the shaft 5. The insulating plate 6 is secured to the shaft 5 by means of set screws 8 and carries a plurality of contact plates 9. The 40 contact plates 9 are resiliently mounted on the insulating plate 6 and are adapted to engage sets of contact members 10 which are mounted on an insulating plate 11. Each plate 9 is secured to the plate 6 by means of two bolts 12, as shown in Fig. 2 of the drawing. The heads of the bolts 12 are formed flush with the surface of the contact plate 9 and collars 13 are suitably secured to the bolts on the opposite sides of the plate 6. Spring members 14 are located

on the bolts 12 between the plate 9 and the plate 6 for exerting a force tending to hold the contact plate 9 towards the insulating plate 11. A limited amount of clearance is provided through the insulating plate 6 for the bolts 12. A guide pin 15 is secured to the insulating plate 6 and projects through a conical opening 16 in the contact plate 9. The contact plates 9 are preferably composed of hardened steel.

The insulating plate 11 is secured to lugs 17 which project from the base 1. The contact members 10 are in the form of bolts having hardened steel heads 18 which are adapted to engage the contact plates 9. The bolts 10 project through the plate 11 and are held in position by means of nuts 19. The terminals of the control system for operating a planer or other machine tool may be connected to the contact members 10. The contact members 10 are arranged in sets of two each, as shown in Fig. 1 of the drawing. The sets are disposed in circular arrangement and the contact members of each set are disposed on a radial line of such circular arrangement. When the switch is in an off position, the contact plates 9 are each located between two sets of contact members. When the shaft 5 is given a movement of rotation in one direction, the contact members on one side of each of the contact plates are bridged and when the shaft is given a movement of rotation in an opposite direction, the contact members on the opposite side of each contact plate are bridged. The insulating plate 11 is held in position by means of set screws 22 which engage lugs projecting from the base 1.

Modifications in the switch and in the arrangement and location of parts may be made in the spirit and scope of my invention and such modifications are intended to be covered by the appended claims.

What I claim is:

1. In a switch structure, the combination 104 with a base member having a stationary plate of insulating material secured to a lug projecting therefrom, and six sets of contact members secured to and projecting through said plate, said sets of contact members being arranged radially in pairs about a circle with the contact members of each pair located on the same radial line, of a short shaft 105 projecting through said base, a second plate of insulating material secured to said shaft 110

and located between said stationary plate and the base member, and a plurality of angularly spaced contact plates resiliently mounted on said second plate and disposed between 5 said pairs of contact members, movement of each contact plate in one direction serving to bridge one set of pairs of contact members and movement of each contact plate in the opposite direction serving to bridge another set of pairs of contact members.

2. In a switch structure, the combination with a base member having a stationary plate of insulating material secured to a lug projecting therefrom, and a plurality of 15 sets of contact members projecting through and secured to said plate in circular arrangement, of a short shaft projecting through and having a bearing in said base member, a second plate of insulating mate-

rial secured to said shaft and located between said stationary plate and the base member, said shaft being located in the center of the circular arrangement of said contact members, a plurality of angularly spaced contact plates resiliently mounted on said 25 second plate, each of said contact plates being located between two sets of contact members for bridging the contact members of one set when the shaft is given a movement of rotation in a forward or in a reverse direction, and a lever secured to said shaft adjacent to the base member for rotating such shaft to effect movement of the second insulating plate.

In testimony whereof, I hereto affix my signature.

ROBERT C. DEALE.
